UNITED STATES PATENT OFFICE.

JOHN V. McMANIS, OF KIRKSVILLE, MISSOURI.

TREATMENT-TABLE.

1,351,482.

Specification of Letters Patent. Patented Aug. 31, 1920.

Application filed June 27, 1917. Serial No. 177,311.

To all whom it may concern:

Be it known that I, JOHN V. McMANIS, a citizen of the United States, residing at Kirksville, in the county of Adair and State of Missouri, have invented certain new and useful Improvements in Treatment-Tables, of which the following is a specification.

My invention relates to improvements in treatment tables, one of its objects is to provide an improved treatment table having a plurality of oscillatable table top sections, another object is to provide improved locking mechanism to lock the top sections in any one of a variety of positions. Another object is to provide improved means to resiliently support the oscillatable sections. Another object is to provide mechanism to take up lost motion and provide against undesirable vibrations. Another object is to provide against the vibration and swaying movement of movable parts carried by the oscillatable top sections. Another object is to provide improved adjustable means to secure a patient in position on the table top.

My invention also comprises certain details of form combination and arrangement, all of which will be fully set forth in the description of the accompanying drawings, in which;

Figure 1 is a plan view of a treatment table embodying my invention.

Fig. 2 is a side elevation of the same.

Fig. 3 is a view similar to Fig. 1 with the top sections omitted.

Fig. 4 is an enlarged bottom plan of the divided oscillatable top section detached from its supporting means.

Fig. 5 is a sectional detail of means to prevent displacement of the adjusting screw due to the oscillatory movement of the top section.

Fig. 6 is a detail of means to lock the oscillatable top sections laterally to any desired position.

Fig. 7 is a bottom plan view of the opposite oscillatable top section.

Fig. 8 is a sectional detail on line $v-v$ of Fig. 7.

Fig. 9 is a sectional detail on line $z-z$ of Fig. 7.

Fig. 10 is a perspective view of a portion of one of the locking members illustrating means to take up lost motion therein.

Fig. 11 is a bottom plan view of the central top section detached.

The accompanying drawings represent the preferred embodiments of my invention in which A represents the base, B a hydraulic plunger or pedestal telescopically mounted in a vertical cylinder in the base and vertically adjustable relative to the base by means of pump mechanism actuated by a hand lever C and operable to pump a liquid from a chamber in the pedestal into the cylinder below the pedestal to elevate the table top, and also at another position of the handle C to release and allow the liquid to return to its storage chamber, thereby lowering the pedestal.

A collar D is fitted over the upper end of the base and a set screw 2 carried thereby bears against a shoe 3 engaging the face of the pedestal, so that when the screw 2 is tightened the shoe is forced against the pedestal and the collar where it fits over the base is also locked to the base, thereby locking the pedestal and base together against vertical or rotary movement. When screw 2 is released the pedestal is adjustable vertically and also rotatably relative to the base.

At its upper end the pedestal is provided with a head or platform E having two downwardly projecting tubular projections 4 and 5, which serve as journals for vertical axles 6 and 7 upon which the respective oscillatable top sections F and H are supported and oscillatable in substantially horizontal planes relative to the pedestal. At the upper end of the axle 6 is a head 8 rigidly mounted upon the axle and provided with a locking segment 9, see Fig. 6, at one side and ears 10 at the opposite side, and a central cross arm 11. A supporting frame 12 is pivotally attached by a horizontal axle 14 to the ears 10, and said frame 12 in turn serves as a support upon which the top section F is supported so as to be oscillatable relative to frame 12 upon a horizontal axle 16, and also adjustable longitudinally along the frame 12. The frame 12 comprises the side bars or ways marked 12 and also the journals 17 for shaft 12 and the cross bars 18 and 19. Mounted to slide endwise on the ways 12 are cross bars 20 and 21 in perforations in which the longitudinal axle 16 is journaled. Cross bars 22, 23, and 24 are at-

tached to the top section F and are provided with bearings for the ends of the axle 16, and feed screw 25 thereby providing for the screw to be turned by a crank arm 26 5 independently of the rotation of the axle 16. The axle 16 therefore serves as a hinge support for the top section F with a limited movement relative to the frame 12. In order to resiliently tension this movement 10 of the top section F upon the axle 16 I provide a projection 27 from the cross bar 23, see Fig. 8, to which tensioning springs 28 are each attached at one end. At the opposite ends springs 28 are attached to eye-bolts 29 passing through lugs projecting from the cross bar 21 and the desired tension applied 15 by adjusting the nuts 30. Stops 31 on cross bar 21 positively limit the movement of the projection 27, but the springs 28 normally 20 serve to hold the top section in a horizontal position and to resiliently limit its movement and return it to position when deflected therefrom.

In order to positively lock the top section 25 F against movement upon the axle 16 I provide lugs 32 on the cross bar 20 and metal shoes 35 on the underface of the top section. A locking member 33 slidable endwise on the axle 16 by means of a hand lever 34, 30 is provided with projecting arms 36 to be interposed with a close fit between the faces of the respective lugs 32 and the respective shoes 35, to positively and rigidly lock the top section against rotation on the axle 16 35 relative to frame 12. In order to adjust the arms 36 to accurately engage between the lugs 32 and shoes 35 to prevent lost motion and consequent objectional vibration and also to compensate for wear at these points 40 I preferably split the arms 36, see Fig. 10, for a portion of their length and provide a tapered screw 37 or other equivalent means to accurately adjust the dimensions of the arms 36 from time to time as may be required.

In order to resiliently tension the movement of the table top section F upon its axle 6 I provide springs 38 and 39 each attached at one end to one end of the cross-bar 11. 50 The opposite ends of said springs are attached to eye-bolts 40 passing through lugs 41 projecting from the head E and to which eye-bolts and springs tension is applied by means of nuts 42. The effect of the springs 38 and 39 is to normally and resiliently hold the top section F in an intermediate position and to return it to such position after having been deflected therefrom. Said springs also tend to counterbalance the overhanging 55 weight of the top section on the axle 6 and to prevent cramping of said axle in its bearings from such cause.

In order to lock the top section F to any 60 adjusted position upon its axle 6, I provide a pair of brake shoes 43 and 44 which rest

upon the head E and are guided by a raised rib 45 thereof. An operating shaft 46 is journaled at 47 to the head E and provided with right and left hand threads to engage the respective brake shoes 43 and 44 to separate or draw them together. The crank arm 48 enables the shaft 46 to be conveniently turned to lock the brake shoes upon the periphery of the segment 9 to hold the top section and its axle 6 rigidly in any desired 75 position.

In order to resiliently support the top section F relative to its axle 14 I provide a slotted frame 49 which is pivotally connected to the lower end of the axle 6. One or more springs 50 are attached at one end to the head 8, preferably by looping them at one end over the axle 14. At the opposite end springs 50 are attached to a carriage 51 movable along the frame 49 by 80 means of a screw rod actuated by means of a crank arm 52, whereby the tension tending to lift the frame 49 may be varied depending upon the position of the carriage 51. The upward thrust of frame 49 is transmitted to the cross bar 19 of the frame 12 by means of a tubular member 53 pivoted at one end to frame 49; an eye-bolt 54 pivotally attached to the cross-bar 19 and telescopically connected to the member 53; and a nut 54' 85 threaded to the shank of the eye-bolt and resting upon the end of member 53. The top section F is thus resiliently supported relative to its axle 14 in a substantially horizontal position, and the tension of 90 springs 50 may be varied to support the weight of different patients thereon. In order to lock the top section F in a substantially rigid position relative to movement upon its axle 14 I provide a locking bar 55 95 pivoted at one end to a collar rigid on the frame 12, and slotted at the opposite end and adapted to be locked by a clamping screw and crank arm 56 to the frame 49. When the locking bar 55 is clamped to 100 frame 49 upward movement of the top section F relative to its axle 14 is prevented, but under pressure downwardly said top section still has a limited resiliently opposed movement due to the thrust being transmitted through the bar 55 from frame 12 to frame 49 which when weight is applied to top section F causes the nut 54' to lift from the end of the tubular member 53.

The feed screw 25 is threaded into the 105 cross bar 18 of frame 12 so that rotation of said screw causes the top section F to travel for a limited distance endwise on the frame 12. This endwise movement provides for applying tension to the spinal column of a 110 patient. A bar 56' pivotally attached at its center to the under face of top section F is provided with sockets at opposite ends into which detachable clips 57 are inserted 115 to provide for attaching the ankles of a patient. A bar 56' pivotally attached at its center to the under face of top section F is provided with sockets at opposite ends into which detachable clips 57 are inserted 120 to provide for attaching the ankles of a patient. A bar 56' pivotally attached at its center to the under face of top section F is provided with sockets at opposite ends into which detachable clips 57 are inserted 125 to provide for attaching the ankles of a patient. A bar 56' pivotally attached at its center to the under face of top section F is provided with sockets at opposite ends into which detachable clips 57 are inserted 130 to provide for attaching the ankles of a patient.

tient by ankle cuffs to said clips, and as the top section F sways horizontally the bar 56' is free to turn upon its pivot and evenly adjust the strain upon the ankles of the patient. In order to prevent displacement or a swaying movement of the crank arm 26 and screw 25 I preferably provide a spring actuated plunger 58, see Fig. 5, to bear upon the screw shaft 25, the tension on said plunger being adjustable by means of a screw 60 bearing upon the spring 59, to force it against the plunger 58.

The top section H is pivotally and resiliently supported relative to the pedestal as heretofore described for the top section F, and identified with like reference letters except that the cross bars 22', 23' and 24' corresponding to the cross bars 22, 23, and 24 are not attached directly to the top section H but are attached to a rectangular metal frame 61 upon which in turn the separate and separable segments 62 and 63 composing the top section H are adjustably mounted.

The segments 62 and 63, see Fig. 4, have rods 64 attached thereto at 65 in pairs, and said rods slide endwise through perforations in the frame, and also slide endwise in guides 66 attached to the segments 62 and 63. The members 65 limit the movement of segments 62 and 63 relative to frame 61 in one direction by contacting therewith, and the stop members 67 contact with frame 61 to limit the movement in the opposite direction. A crank shaft 68 is journaled in a bracket attached to frame 61, and is pivotally connected to one end of each of the links 69 and 70. The opposite ends of the links are pivotally connected to the blocks 71 and 72 attached respectively to the segments 62 and 63. A half rotation of the crank shaft 68 shifts the centers on which the links are pivoted to the crank shaft 68 from one point of dead center to the other and moves the segments 62 and 63 to and from each other, locking them at each extremity of their movement to the frame 61 by reason of the stops 65 and 67, and the dead center positions of crank shaft 68.

The feed screw 25 of top section H has a knurled head 26' instead of a crank 26. Sockets 73 are attached to frame 61 to detachably support a bracket 74 to which a flexible harness about the neck of a patient may be attached in applying strain to the spine. The rotary movement of the top section on its vertical axle 7 is stopped at any desired position of top section H by means of brake shoes in pairs engaging a segment 9' carried by the head 8' attached to the axle 7. The top section H is resiliently tensioned relative to movement upon the axle 7 by means of springs 38' and 39' as described for the top section F.

The intermediate top section G is supported relative to the head E by means of a shaft 76 rotatably mounted in journals on the head E, see Fig. 11, and a shaft 77 journaled to brackets on the under face of section G. The two shafts are connected together by means of links 78, and are each provided with an operating lever. The shaft 76 has rigidly attached thereto cams 79 which serve to engage and raise or lower one end of top section G as may be desired. The shaft 77 is provided with similar cams 80 to engage shoes on the head E and to thereby raise or lower the opposite end of section G, the section G is thus capable of being adjusted to four different positions.

The combination of two pivotally and resiliently supported top sections enables different portions of the patient to be exercised and different movements employed without changing his position on the table as each section may be locked entirely or partially against movement and the remaining movements employed. Also either section may be locked laterally out of the medial or normal position. When the ankles of the patient are secured to the clips 57 and the top section F oscillated laterally the pivotal movement of member 56' provides for a substantially uniform and equal distribution of strain on the respective ankles instead of an alternate strain on one ankle and then on the other.

The top section G may be removed or omitted if desired, but is preferably employed as illustrated. The resilient support for the top sections relative to rotation on the axles 16 provides for holding said top sections to a normal predetermined position, from which one or both may be oscillated by the application of force, to a limited extent in either direction. The great variety and combination of movements of the table top sections jointly and separately are important in securing the desired exercise and articulation of the segments of the spinal column, and also the softer parts and organs influenced by such movements. The vertical adjustment of the table provides for convenient application of force to secure the desired table movements and differences in size and weight of patients.

The mechanism herein illustrated and described is capable of considerable modification without departing from the principle of my invention.

Having described my invention, what I claim is—

1. A treatment table comprising a base, a pedestal vertically adjustable relative to said base, and a plurality of table top sections each pivotally and resiliently supported upon and relative to said pedestal.

2. A treatment table comprising a sup-

- porting pedestal and a plurality of table top sections each pivotally and resiliently supported upon and relative to said pedestal and having universal movement relative to said pedestal.
3. A treatment table comprising a pedestal and a plurality of table top sections arranged end to end and each pivotally and resiliently supported relative to said pedestal.
- 10 4. A treatment table comprising a pedestal, a plurality of table top sections arranged end to end and each pivotally and resiliently supported relative to said pedestal and means to lock said top sections respectively rigidly to said pedestal.
- 15 5. A treatment table comprising a pedestal, a plurality of table top sections each pivotally and resiliently supported and movable in a plurality of different planes relative to said pedestal, and means to independently lock each top section to said pedestal against movement in one of said planes.
- 20 6. A treatment table comprising a base, a pedestal vertically adjustable relative to said base, a plurality of table top sections each pivotally and resiliently supported and movable in a plurality of different planes relative to said pedestal, and independent means to separately lock each top section to said pedestal against movement in either of its planes of movement.
- 25 7. A treatment table comprising a base, a pedestal vertically adjustable relative to said base, a plurality of table top sections arranged end to end and each pivotally and resiliently supported relative to said pedestal, one of said top sections being longitudinally separated into segments.
- 30 40 8. A treatment table comprising a pedestal and a plurality of table top sections arranged end to end and each pivotally and resiliently supported relative to said pedestal, one of said top sections being longitudinally of the table divided into two separable segments.
- 35 45 9. A treatment table comprising a pedestal, an intermediate top section and two pivotally and resiliently supported top sections at opposite ends of said intermediate top section.
- 50 55 10. A treatment table comprising a base, a pedestal vertically adjustable relative to said base, an intermediate top section, and two pivotally and resiliently supported top sections at opposite ends of said intermediate top section.
- 60 65 11. A treatment table comprising a pedestal, an adjustable intermediate top section, and two pivotally and resiliently supported top sections at opposite ends of said intermediate top section.
12. A treatment table comprising a pedestal, an intermediate top section and two pivotally and resiliently supported top sections
- at opposite ends of said intermediate top section, one of said pivotally supported top sections being longitudinally of the table divided into two separable segments.
13. A treatment table comprising a main top section, an intermediate top section and an auxiliary top section arranged end to end, said auxiliary top section separately pivotally and resiliently supported upon a vertical axle, a transverse horizontal axle and a longitudinal axle.
14. A treatment table comprising a main table top section, and an auxiliary table top section pivotally supported upon an axle substantially parallel thereto and longitudinally thereof and means to resiliently hold said auxiliary top section in a predetermined position relative to said axle.
15. A treatment table comprising a base, a pedestal vertically adjustable relative to said base, a main table top section supported upon said pedestal, an auxiliary table top section rotatably supported relative to said pedestal upon an axle substantially parallel to said auxiliary top section and longitudinally thereof, and means to resiliently hold said auxiliary top section in a predetermined position relative to said axle.
16. A treatment table comprising a main table top section and an auxiliary table top section, said auxiliary top section being pivotally and resiliently supported relative to said main top section separately upon a vertical axle, a transverse horizontal axle and a longitudinal axle substantially parallel to said auxiliary top section, and upon which said auxiliary top section is adjustable endwise.
17. A treatment table comprising a pedestal, a main table top supported by said pedestal, an auxiliary table top rotatably supported relative to said pedestal upon an axle substantially parallel to said auxiliary top section and longitudinally thereof, means to resiliently hold said auxiliary top section in a predetermined position relative to said axle, and means to rigidly lock said auxiliary top section against rotation upon said axle.
18. A treatment table comprising a main table top section and an auxiliary table top section, said auxiliary top section being pivotally and resiliently supported relative to said main top section separately upon a vertical axle, a transverse horizontal axle and a longitudinal axle substantially parallel to said auxiliary top section, and independent means to separately lock said auxiliary top section against rotary movement upon said respective axles.
19. A treatment table comprising a main table top section, an auxiliary table top section rotatably and resiliently supported relative to said main top section, and means pivotally attached at an intermediate point to

said auxiliary top section and at opposite ends of which the ankles of a patient are secured, to assist in equalizing the strain upon the respective ankles when said auxiliary top section is oscillated.

20. A treatment table comprising a main table top section, an auxiliary table top section rotatably and resiliently supported relative to said main top section, means to attach the upper extremity of a patient to said main top section, and means pivotally attached at an intermediate point to said auxiliary top section and to opposite ends of which the lower extremities of a patient are respectively secured, to assist in equalizing the strain upon the lower extremities of the patient when said auxiliary top section is oscillated.

21. A treatment table comprising a main table top section and an auxiliary table top section rotatably and resiliently supported relative to said main top section upon a substantially vertical axle, a substantially vertical supporting axle, a segment carried rigidly by said axle, means to engage said segment to rigidly lock said auxiliary top section against rotation upon said axle at any desired position of adjustment.

22. A treatment table comprising a main table top section and an auxiliary table top section rotatably supported relative to said main top section upon a vertical axle and an axle longitudinally of and substantially parallel to said auxiliary top section, means to resiliently support said auxiliary top section in a predetermined position relative to said longitudinal axle, and means to lock said auxiliary top section against rotation upon said longitudinal axle.

23. In a treatment table a table top section oscillatable upon a vertical axle and upon an axle longitudinally of and substantially parallel to said auxiliary top section, means to resiliently support said auxiliary

top section in a predetermined position relative to said longitudinal axle, means to lock said auxiliary top section against rotation upon said longitudinal axle, and means to adjust said locking means to provide for wear and to prevent vibration of said auxiliary top section relative to said longitudinal axle while being oscillated upon said vertical axle.

24. In a treatment table a table top section oscillatable upon a substantially vertical axle, a transverse substantially horizontal axle, and an axle longitudinally of and substantially parallel to said auxiliary top section, means to lock said auxiliary top section independently against rotation upon said respective axles, means to resiliently support said top section in predetermined position relative to said respective axles, and means to adjust one of said locking means to provide for wear and to prevent vibration of said auxiliary top section relative to one of said axles while being oscillated upon another of said axles.

25. In a treatment table a table top section oscillatable upon a substantially vertical axle and upon an axle longitudinally of and substantially parallel to said auxiliary top section, an adjusting screw to adjust said auxiliary top section upon said longitudinal axle relative to said vertical axle, means to resiliently support said auxiliary top section in a predetermined position relative to said vertical axle, and means to retain said adjusting screw in its adjusted position against displacement due to the oscillatory movement of said auxiliary top section and its adjusting screw.

In testimony whereof I have affixed my signature in the presence of two witnesses.

JOHN V. McMANIS.
